UNITED STATES PATENT OFFICE.

FRANK ACHILLE BIENVENU, OF MONTREAL, QUEBEC, CANADA, ASSIGNOR, BY MESNE ASSIGNMENTS TO CATELLI MACARONI PRODUCTS CORPORATION LIMITED, OF MONTREAL, CANADA.

WORKSTAND.

Application filed August 1, 1927. Serial No. 209,952.

The invention relates to a work stand, as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to facilitate the operations in a factory particularly in canning establishments when a table must be adaptable for various uses and in different 15 places; to construct a mechanism for elevating and lowering a table shelf, box or other device, that may be operated with ease and offer no difficulties to the workmen in the pursuit of their duties; to reduce the 20 number of appurtenances necessary to any plant and thereby insure sanitary and cleanly methods; and generally to provide a simple, efficient and durable accessory to a machinery plant.

25 In the drawings, Figure 1 is a side elevation of the table.

Figure 2 is a plan view of the mechanism showing the table top removed.

Figure 3 is an enlarged perspective view 30 of the table partly broken away.

Figure 4 is a side elevation of a machine showing another application of the mechanism.

Like numerals of reference indicate corresponding parts in the various figures.

35 Referring to the drawings, the permanent and fixed frame 9 is shown as formed of four legs 10 joined by the side braces 11 and end braces 12. The elevatable frame 13 is formed of the legs 14 corresponding to the legs 10, and the side braces 15 and end braces 16. The frame 13 fits into the permanent or fixed frame 9 and carries the table top 17 here shown as scooped out at 18 and 40 19 to fit to different machines, the shapes or positions of these scoops being by no means arbitrary, as they are made to suit the circumstances of use. The top 17 is preferably covered with metal or other serviceable covering according to the purpose for which this invention may be adapted.

45 The parallel arms 20 and 21 are joined and spaced at the ends by the yoke 23 and at one end are mounted pivotally on the rail

24 rigidly secured in the permanent frame 55 9 to two end legs thereof and at the other end are mounted on the rail 25 rigidly secured to two end legs of the elevatable frame 13 at the opposite end of the table. The lever arm 26 is pivotally mounted on the 60 spindle 27 between the parallel arms, thereby forming a lazy tong lever arrangement of arms adapted to lift the table.

The arm 26 is pivotally mounted at one end on the rail 28 secured to a pair of end 65 legs of the elevatable frame 13 and at the other end to the rail 29 secured in the fixed frame 9 thus in the lazy tong movement the table top is raised and lowered.

The operating screw 30 is rotatably secured in the nut 31 and in the arm 26 supporting said nut and screw. The screw 30 is also held at its upper end by the yoke 23, therefore by turning the crank handle 33 mounted on the upper end of the screw 30 70 75 the ends of the arms are drawn together or separated according as the the table top is being raised or lowered. At the other end the guide rod 34 is swivelly attached to the arm 26 and slidably arranged with the plate 80 35 from the arms 20 and 21 said guide rod 34 and 35 being locked to the adjusted position by the clamp 36 operated by the handle 37.

85 In Figure 4 the same mechanism is attached to a box 38 lifted in the frame 39 standing on the floor, simply showing another application of the same device.

In the operation of the invention the table is moved to the machine and elevated or lowered as the case may be to bring it flush with the shelf of the machine and this is done by turning the handle of the operating screw and locking it at the other end.

90 What I claim is:—

95 1. In a work stand, a standing frame and an elevatable frame, pivot bearings in rail form connecting the several end legs of said frames in pairs, parallel arms joined and spaced by yokes, at the ends and centrally 100 by a spindle forming a pivot bearing, a single arm centrally mounted on said spindle pivot bearing, said parallel arms being mounted at one end on a rail pivot bearing on said standing frame and on a rail pivot bearing at the elevatable frame and said single arm being mounted at one end on a rail pivot bearing of the elevatable frame and on a 105

rail pivot bearing of the standing frame at the other end, an operating screw engaging said parallel and single arms at one end for separating and drawing them together and a guide rod having a locking device for holding the arms apart at the other ends.

2. A work stand comprising a plurality of frames, having their end legs joined by a plurality of rails and slidably arranged one

within the other, crossed lever arms pivotally mounted on said rails, one to each frame at either end, a crank member adapted to spread said arms at the ends, and means for holding the arms and consequently the frames to their adjusted positions.

15

Signed at Montreal, Canada, this 7th day of July, 1927.

FRANK ACHILLE BIENVENU.
